CLAIM

The ornamental design for a led power supply as shown and described.

DESCRIPTION

FIG. 1 is a front, top, right perspective view of a first embodiment of a led power supply showing our new design; FIG. 2 is a front view of FIG. 1; FIG. 3 is a rear view FIG. 1; FIG. 4 is a left view FIG. 1; FIG. 5 is a right view FIG. 1; FIG. 6 is a top view FIG. 1; FIG. 7 is a bottom view FIG. 1; FIG. 8 is a front, top, right perspective view of a second embodiment of a led power supply showing our new design; FIG. 9 is a front view of FIG. 8; FIG. 10 is a rear view FIG. 8; FIG. 11 is a left view FIG. 8; FIG. 12 is a right view FIG. 8; FIG. 13 is a top view FIG. 8; and, FIG. 14 is a bottom view FIG. 8.

The broken lines shown on the drawings depict portions of the led power supply that form no part of the claimed design.

1 Claim, 14 Drawing Sheets
